UNITED STATES PATENT OFFICE.

SMEDLEY D. BUTLER, OF WEST CHESTER, PENNSYLVANIA, ASSIGNOR OF ONE-HALF TO
PETER ABRAMS, OF PHILADELPHIA, PENNSYLVANIA.

INFANTRY-FIRE-CONTROL RULE OR SCALE.

1,277,191.

Specification of Letters Patent. Patented Aug. 27, 1918.

Application filed August 23, 1915. Serial No. 46,960.

To all whom it may concern:

Be it known that I, SMEDLEY D. BUTLER, a citizen of the United States, and a resident of West Chester, Chester county, Pennsylvania, have invented an Improved Infantry-Fire-Control Rule or Scale, of which the following is a specification.

My invention relates to devices employed to regulate or indicate the proper sighting 10 of a rifle in that form of warfare in which the enemy is invisible to the firing line; and the object of my invention is to provide a structure designed to indicate a certain line or area at a given range whereby infantry 15 fire may be regulated or controlled in order that the most effective use of the ammunition employed may be secured.

My invention comprises a scale or ruler which may be approximately eight to twelve 20 inches in length, and about an inch in diameter, and which may be hexagonal, round or such other shape as may be desired, which scale or ruler carries slideable reference members. The scale or ruler is provided with a 25 cord so that it may be worn about the neck of an officer or other person serving as a fire control leader, the cord being of such a length that the scale or ruler may be held at a point substantially twelve inches from 30 the eye of the observer when the cord is fully extended.

These and other features of my invention are more fully described hereinafter, reference being had to the accompanying drawings, in which:

Figure 1, is a perspective view of one form of scale or ruler embodying my invention;

Fig. 2, is a longitudinal sectional view of the same;

Fig. 3, is a cross sectional view;

Figs. 4 and 5, are perspective views of other forms of scales or rulers within the scope of my invention;

Figs. 6 and 7, are cross sectional views of the same respectively;

Fig. 8, is a view showing the manner in which the scale or rule is used, and

Fig. 9, is a diagrammatic view showing the manner in which fire from a single 50 squad is distributed.

The scales which I employ, preferably twelve in number, although there may be more if desired, are carried upon the surface of a ruler 1, which may be round, hexagonal, octagonal, or any other shape de-

sired. Slidably mounted with respect to the scale or ruler are reference members or pointers 2, which are employed in connection with the scale markings to indicate the number of men of each firing squad, platoon 60 or division; each unit division representing a squad of eight men.

In the form of structure shown in Figs. 1, 2 and 3, the bar constituting the ruler is round and carries twelve scales. The reference members or pointers 2 are annular bands, and one or more of the same may carry numbers indicating the yard ranges. They may be grooved internally at 4 to fit over longitudinal guides 5 carried by the 70 bar, or the latter may be grooved and the reference members provided with projections to fit the same, as shown in Fig. 5. The reference members 2 may additionally be provided with spring fingers 6 to increase 75 the friction and insure them retaining their position when set.

In the form of structure shown in Figs. 4 and 6, the reference members 2^a may have laterally disposed spring fingers 6^a to hold 80 them frictionally in place, or in the form shown in Figs. 5 and 7, in which a round ruler is indicated, the latter may be grooved at 4^a for the reception of lugs 5^a carried by the reference members 2^b.

The rule is preferably hollow and may have knobs or handles 7 at the ends connected to removable screw caps or plugs 8 closing the open ends of the rule, as shown in Fig. 2. The knobs may carry various 90 tools or instruments of value to the user, as for instance, a compass 10, a whistle 11, or a pencil 12, or any other small member of a similar character of utility in the field. A cord 13 is connected to the ends of the 95 ruler so that it may be held at a proper distance from the eye of the user, about twelve inches. If desired, in order that the ruler may be turned relatively to the eye of the observer without winding the cord, the latter may be attached to annular bands at the ends of the ruler rotatable with respect to the same.

In use, the scale is hung around the neck of the user by the cord, which is of such 105 length that when extended to its greatest extent the rule may be held substantially twelve inches from the eye.

The zone of attack will be any space at the known range observed between any two of 110

- the reference members; one of said reference members being alined with some prominent object at the range under consideration, such as a tree, bush, rock or other natural mark.
- 5 The ranges, of course, are obtained by the usual well known means and are a known or substantially known quantity; the object of the present device being to effect an equally distributed fire at definite lateral spaces, 10 from a firing squad, company, or battalion, at any given range.

The unit divisions of the respective scales, each subtend, when the rule is held twelve inches in front of the eye, one squad front, 15 or eight yards, at eight hundred, nine hundred, ten hundred, eleven hundred, twelve hundred yards &c., respectively, depending upon the number of scales carried on the ruler.

- 20 A squad front is selected, as the squad is the unit most likely to remain at full strength and is the most suitable unit for use in fire distribution. Three or more sliding indicators are provided, (usually three) one 25 being used to cover the "reference point," the other two to bracket the objective. At one thousand yards, each division on the one thousand yard scale is about equal to eight points of windage, and the members of the 30 squad, each aiming at the one point, will set their windage sight laterally at the one thousand yard range one point with respect to their fellows; that is to say, if the aiming point is to the left of the squad, No. 1 man 35 on right will set his windage scale to the right the full distance or eight points, No. 2 man will set his at seven points, and so on until No. 8 man will set his sight at one point, as indicated in Fig. 9.

- 40 *Object to be obtained by its use.*—Under modern conditions troops are seldom visible on battle-fields, hence targets for troops firing are rare. It is necessary, in order to produce any results, to have an aiming point 45 for each soldier firing, therefore, as the enemy is not visible to each man, there will be great waste of ammunition unless some other aiming point is given him.

- (a) By the use of this ruler auxiliary or 50 false aiming points, trees, bushes, fences, houses, telegraph poles, etc., in front of the enemy's line; in his line, or in rear of it, are selected, and fire data given each soldier, causing an even dispersion or distribution of 55 shots over a target at the indicated range.

- (b) By its use a uniform method of describing or picking up points is assured 60 throughout an organization, and should the selected-point become confused with others, owing to excitement, change of position, etc., it may be rapidly and accurately found again.

- (c) By its use only the company commander need actually see or know the exact 65 position of the enemy, and the men firing

need only see the aiming point; their shots being brought into the target by sight corrections given by fire directors; control officers, non-commissioned officers, &c.

A typical description of its use is as follows:

A regimental commander selects a prominent object in the landscape, one that cannot be mistaken, as a "reference point"; assembles his battalion commanders, who are 75 equipped with this ruler; points out the position of the enemy and the reference point, and assigns each battalion commander his objective in terms of squad fronts, as per example.

Each battalion commander places one of the reference members 2 on "reference point", and brackets his objective with other indicators on his scale, assembles his company commanders, points out "reference 85 point" and assigns objective to each company as per example.

Each company commander places one of the reference members 2 on "reference point", and brackets his objective with other 90 indicators, picks out aiming points, within his objective, in the enemy's line, in rear or a short distance in front of it, which are visible from his firing line, and not more than six squad fronts or forty-eight yards 95 apart; (for convenience of aiming this distance should not be more than twenty-five yards apart). He then assembles his section leaders, points out reference point and if possible, the enemy, and by the use of 100 scale on ruler, each aiming point as per example.

Section or platoon leaders place one of the reference members 2 on "reference point" and bracket their objective with 105 other indicators by means of ruler, point out aiming points to squad leaders and give windage points to each squad necessary to distribute fire over section objective.

It will be understood also, that my improved rule or scale may be employed in a vertical position to develop the elevation of a gun for the respective ranges by the well known methods of range finding.

I claim:

1. A scale or rule for controlling infantry fire, comprising a bar divided into longitudinal sections representing ranges in yards, each longitudinal section subdivided equally into unit sections bearing a definite relation to the ranges of the first mentioned sections, and reference members slidably mounted on said bar.

2. A scale or rule for controlling infantry fire, comprising a bar divided into longitudinal sections representing ranges in yards, each longitudinal section subdivided equally into unit sections bearing a definite relation to the ranges of the first mentioned sections, reference members slidably mounted on said 130

bar, and guiding means for said reference members.

3. A scale or rule for controlling infantry fire, comprising a bar divided into longitudinal sections representing ranges in yards, each longitudinal section subdivided equally into unit sections bearing a definite relation to the ranges of the first mentioned sections, reference members slidably mounted on said bar, guiding means for said reference members, and friction means carried by said reference members to hold them in adjusted positions on said bar.

4. A scale or rule for controlling infantry fire, comprising an elongated bar divided into longitudinal sections representing ranges in definite units of measurement, each of said longitudinal sections being sub-

divided equally into unit sections bearing a definite relation to the ranges of the first-mentioned sections, and a reference member slidably mounted on said bar.

5. A scale or rule for controlling infantry fire, comprising an elongated bar divided into longitudinal sections representing ranges in definite units of measurement; each longitudinal section being subdivided equally into unit sections bearing a definite relation to the ranges of the first-mentioned sections, reference members slidably mounted on said bar and means connected to the ends of such scale or rule whereby it may be conveniently held a proper distance from the eye to subtend each of said unit divisions one squad front at the respective ranges.

SMEDLEY D. BUTLER.

Copies of this patent may be obtained for five cents each, by addressing the "Commissioner of Patents
Washington, D. C."

It is hereby certified that in Letters Patent No. 1,277,191, granted August 27, 1918, upon the application of Smedley D. Butler, of West Chester, Pennsylvania, for an improvement in "Infantry-Fire-Control Rules or Scales," an error appears requiring correction as follows: Sheet 3 of the drawings, containing Fig. 10, should be canceled, it forming no part of the Letters Patent; and that the said Letters Patent should be read with this correction therein that the same may conform to the record of the case in the Patent Office.

Signed and sealed this 15th day of April, A. D., 1919.

[SEAL.]

F. W. H. CLAY,

Acting Commissioner of Patents.
